(57) **CLAIM**

The ornamental design for a farm stand, as shown and described.

DESCRIPTION

FIG. 1 is a perspective view of a farm stand, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings represent portions of the farm stand that form no part of the claimed design, including the wavy roof, handles, hinges, lock, and wheels.

1 Claim, 7 Drawing Sheets
